DESIGN FOR A FOOD MIXER

Benjamin E. Lawrence, Chicago, Ill.

Application January 23, 1936, Serial No. 60,744

Term of patent 3½ years

To all whom it may concern:

Be it known that I, Benjamin E. Lawrence, a citizen of the United States, residing at Chicago, county of Cook, and State of Illinois, have invented a new, original, and ornamental Design for a Food Mixer, of which the following is a specification, reference being had to the accompanying drawing, forming a part thereof.

Fig. 1 is a top plan view of a food mixer embodying my new design.

Fig. 2 is a side elevation of the same.

I claim:

The ornamental design for a food mixer substantially as shown.

BENJAMIN E. LAWRENCE.
